(57) **CLAIM**

The ornamental design for an ALIF retractor assembly, as shown and described.

DESCRIPTION

FIG. 1 is a perspective view of the ALIF retractor assembly of the instant invention;

FIG. 2 is a left side view thereof;

FIG. 3 is a right side view thereof;

FIG. 4 is an end view thereof;

FIG. 5 is an opposite end view thereof;

FIG. 6 is a top view thereof;

FIG. 7 is a bottom view thereof; and,

FIG. 8 is an exploded view of the ALIF retractor assembly.

1 Claim, 5 Drawing Sheets
